(57) **CLAIM**

The ornamental design for a wall-mounted kiosk, as shown and described.

DESCRIPTION

FIG. 1 is a front and right side perspective view of a wall-mounted kiosk showing my new design;

FIG. 2 is a front elevational view thereof;

FIG. 3 is a right side elevational view thereof; and,

FIG. 4 is a left side elevational view thereof.

The broken line disclosure of portions of the article in which the design is embodied forms no part of the claimed design.
